UNITED STATES PATENT OFFICE.

FREDERICK C. WARNE, OF MANSFIELD, OHIO, ASSIGNOR TO RODERICK LEAN MANUFACTURING COMPANY, OF MANSFIELD, OHIO, A CORPORATION OF NEW JERSEY.

DISK HARROW.

1,344,159.

Specification of Letters Patent. Patented June 22, 1920.

Application filed May 16, 1918. Serial No. 234,873.

To all whom it may concern:

Be it known that I, FREDERICK C. WARNE, a citizen of the United States, residing at Mansfield, in the county of Richland and 5 State of Ohio, have invented certain new and useful Improvements in Disk Harrows, of which the following is a specification.

My invention relates to improvements in disk harrows, and more particularly to that 10 class or type known as "double" or "tandem" disk harrows, in which front and rear units are employed, each unit embodying a pair of adjustably mounted rotary disk gangs adapted to be angled or turned in 15 opposite directions relative to each other and to the line of draft, as disclosed for example in Patent No. 1,189,890, of July 4th, 1916.

This invention further relates to that class 20 or type of double disk harrows known as "engine disk harrows", the present improvements being particularly designed and adapted for use in connection with an engine or tractor, and with this end in view, 25 my improvements relate particularly to improved draft connections for such implements and improved lever and lever actuated locking and adjusting mechanism whereby the disk gangs thereof may be 30 readily moved to and secured in any desired angular position relative to each other and to the line of draft by the operator of the tractor while in the seat or cab of the latter, the construction and arrangement of 35 the parts being such that when the disk gangs are locked in their normal working or fully angled position, or in an intermediate angular working position, and are relatively released or unlocked by the operator 40 through such mechanism while the tractor is in motion, such disk gangs will automatically assume through such draft connections their non-working or non-angled transporting position, or less angular working 45 position, as the case may be, and as the operator may elect, and may be stopped and locked in such elected position while the tractor is in motion. Furthermore, if desired, the disk gangs may be manually 50 moved to a more angular or to a fully angled working position, while in motion, through a single hand lever with a minimum expenditure of energy by the operator.

A further object is to provide a generally

improved lever actuated disk harrow of this 55 class having its parts so constructed, arranged and disposed relative to each other as to give the requisite strength, flexibility and general adjustability which experience and the varying demands of actual service 60 have shown to be necessary or desirable, and to this end I provide two draft or reach bars pivotally connected to the rear unit or section and extending forwardly and in converging relation to each other and pivotally 65 connected to the front unit or harrow section at two points equally distant from the longitudinal center of the harrow or line of draft, as disclosed in my said patent hereinbefore referred to, such connection with 70 the front harrow section, however, in the present instance, being effected through relatively movable draft connections operable and adjustable on the front or draft frame through the medium of a single hand 75 lever within ready reach of the operator of the tractor.

With the above mentioned and other ends in view, the invention consists in the novel construction, arrangement, and combination 80 of parts, hereinafter described, illustrated in one of its embodiments in the accompanying drawings, and particularly pointed out in the appended claims.

Referring to the drawings, forming a part 85 of this specification, Figure 1, is a top plan view of a disk harrow constructed in accordance with this invention, the disk gangs being in their non-working or non-angled transporting position, the hand lever being shown in section and the scraper blades being removed for the purpose of clearer 90 illustration of the parts.

Fig. 2, an enlarged cross sectional view taken on line 2—2, of Fig. 1. 95

Fig. 3, a top plan view of the disk harrow, the disk gangs being in their extreme angled or working positions, the central or relatively movable draft block and its connected draft and reach bars attached to the 100 inner ends of the front disk gangs and to the pivoted portions of the rear disk gangs, respectively, being in their relatively rear-most positions.

Fig. 4, a perspective view of the improved 105 disk harrow, the improved lever and lever actuated adjusting and locking mechanism being in unlocked position, preparatory to

moving the disk gangs from their fully angled working position to an intermediate angular working, or to their non-angled transporting position, by the forward draft on 5 the implement.

Fig. 5, a perspective view of the fixed draft element or reach bar and the relatively longitudinally fixed and movable draft connections, together with the guiding element and equalizing bar for the latter, and illustrating also the flexible connections of the longitudinally movable draft connections or reach bars with the inner ends of the pivoted front tillage gangs.

Fig. 6, an enlarged central longitudinal sectional view of the stub pole and longitudinally movable draft appliance, the dotted lines representing the throw of the working lever during a single working impulse in 10 manually moving the disk gangs from a non-angled to an angular working position, or from one angular position to a more angular working position.

Fig. 7, a similar view, showing the actuated pawl and locking dog in released position relative to the rack of the longitudinally movable draft bar, preparatory to the movement of the latter by the forward draft on the implement.

Fig. 8, a cross sectional view taken on line 8—8, of Fig. 6.

Fig. 9, a perspective view of the draft bar and draft block, detached.

Fig. 10, a perspective view of the under-35 side of the locking dog, detached.

Similar numerals of reference designate like parts throughout all the figures of the drawings.

The improved harrow or tillage implement comprises a front harrow section or unit and a rear or trailing harrow section or unit. The front and rear harrow sections may be of any suitable and conventional form, and for the purposes of illustration I 40 have shown my improved draft appliance and its connections applied to or embodied in a double or tandem disk harrow of the general form of that disclosed in my former patent hereinbefore referred to.

The front harrow section or unit is provided with a suitable draft frame consisting, in the present instance, of a transverse bar 1, and a curved draft frame member 2, the latter having its forward middle portion 45 secured to a stub-pole 3, which latter is made up of spaced angle bars secured at their rear to the transverse bar or member 1, and, in the present instance, forming a guide or slideway for the improved longitudinally 55 movable draft appliance hereinafter described.

As a means of connecting the draft frame to the front disk gangs 4, draft bars or links 5, are pivotally connected to filler blocks 2^a, 60 said draft bars extending rearwardly be-

neath the transverse bar 1, and being flexibly connected to the axle boxes 6, somewhat beyond the centers of the disk gangs, so that the inner ends of the latter will have a tendency to swing rearwardly and assume a rearwardly converging position. As a means of supporting and maintaining the draft bars 5, in proper horizontal relation to the transverse bar 1, supporting clips 7, are pivotally mounted upon the filler blocks 2^a, and are 70 secured by means of pivot bolts 5^a, secured to the forward ends of the draft bars 5, said clips 7, extending rearwardly and being secured to the top intermediate portions of the bars 5, by means of pivot bolts 7^a, and as 80 a further means of securing the draft frame to the front disk gangs draft bars or links 8, are connected by the pivot bolts 5^a, above the supporting clips 7, and extend upwardly and rearwardly and are flexibly connected 85 to the upper or transverse bars 9, of the front gang frames by means of pivot bolts 9^a. The gang frame bars 9, are connected to the disk gangs 4, by means of supporting bracket or brace members 9^b, extending 90 downwardly and suitably secured to the axle boxes 9^c.

The rear harrow section or unit, in the present instance, comprises a pair of rear disk gangs 10, suitably mounted and supported in gang frames 11, the latter being 95 provided with supporting brackets 11^a, connected to axle boxes 12.

The rear disk gangs 10, in the present instance, are pivotally connected and held in 100 proper spaced relation at all times by means of a transversely extending rear bar forming a rear harrow frame 13, provided at its ends with pivot bearing bolts 14, suitably connected to the rear gang frames 11, of the 105 rear gangs. It will be observed that the pivot or swivel bolts 14, are located beyond the centers of the rear gang frames, so that the inner ends of the rear gangs, if left unsupported or free, will have a tendency to 110 swing rearwardly and away from their normal forwardly converging working position, as shown in Fig. 3, of the drawings, and assume a straightened non-working position relative to each other, as shown in Fig. 1, 115 of the drawings, when permitted to swing on their pivots 14, through their draft connections, as hereinafter described.

As a means of connecting the inner ends of the rear gangs 10, to the front harrow 120 section, longitudinally fixed draft bars 15, are provided, said bars being connected at their rear ends to bearing plates 15^a, of the gang frames, and being also provided with brace members 15^b, suitably secured to the 125 bearing axle blocks at the inner ends of the rear gangs, the forward ends of the draft bars 15, in the present instance, being flexibly connected to a fixed draft element or median reach bar 16, the latter extending for- 130

wardly and being secured, in the present instance, to the transverse bar 1, and between the members of the stub-pole 3, by means of securing bolts 16^a. The forward 5 ends of the draft bars 15, are secured to the draft element or reach bar 16, by means of pivot bearing bolts 16^b, at points equally distant from the line of draft, or the common longitudinal center of the implement, and, 10 in the present instance, said fixed draft bars 15, extend rearwardly to the inner ends of the rear gangs in a rearwardly diverging relation, and as compared with the movements of the draft bars attached to my im- 15 proved draft appliance hereinafter described, these draft bars 15, together with the draft bars or links 5 and 8, are longitudinally fixed relative to the frame units and tillage gangs, in order that the func- 20 tions of the draft appliance and its longitudinally movable draft bars may be performed, as hereinafter described.

Referring now to the improved draft appliance and its gang connecting, adjusting 25 and controlling mechanism, whereby the operator of the tractor, while in his usual driving position on the latter, and when the disk gangs are locked in their normal or fully angled positions, or in intermediate angled 30 positions, and are relatively released or unlocked while the tractor is in motion, will permit such gangs to automatically assume, through such draft connections, their non-working non-angled transporting position, 35 or various angular working positions, as the case may be, and as the operator may elect, and whereby the same may be stopped and locked in any such elected positions, it will be seen that the improved draft appliance 40 comprises a longitudinally movable draft member or element, mounted, in the present instance, in the stub-pole 3, of the draft frame, and consisting, in the present instance, of a draft block or head 17, adapted 45 to slide along the angular members of the stub-pole 3, said block 17, being controlled by a longitudinally movable draft bar or yoke 18, terminating at its forward end in a draft loop 18^a. The draft loop 18^a, is adapt- 50 ed to be attached to the tractor, and as a means of operating and controlling the movements of the draft bar or yoke 18, and draft head 17, and the connections leading from the latter to the disk gangs, as hereinin- 55 after described, one side of the draft bar or yoke 18, is provided with a toothed rack 18^b, and as a means of enabling the operator to readily move the draft block or head 17, and its attachments, together with the stub- 60 pole 3, and its attachments, relative to each other, an operating hand lever 19, is pivotally mounted on the stub-pole 3, through the medium of a suitable bearing bolt 19^a, said hand lever extending upwardly through 65 a suitable guide bracket or segment 20, and

within ready reach of the operator of the tractor.

As a means of intermittently engaging and feeding the draft bar or yoke 18, rearwardly through working impulses imparted 70 to the hand lever 19, the lower portion of the latter is provided with a pivoted pawl 21, adapted to be moved to a released position by means of a rod 22, leading to a releasing lever 23, at the handle portion of the 75 hand lever 19.

As a means of preventing any shifting or retrograde movement of the draft bar 19, and toothed rack 18^b, after each working impulse given to the hand lever 19, the 80 stub-pole 3, is provided at one side with a pivoted locking dog 24, the latter being provided with a detent 24^a, adapted to normally ride upon the teeth of the rack 18^b, and as a means of simultaneously releasing 85 the pivoted pawl 21, and locking dog 24, and holding such parts in such released position for the extended shifting or forward movement of the draft yoke 18, and its attachments, by the forward draft of 90 the tractor, the locking dog 24, is provided with an overhanging ledge or projection 24^b, so that when the free end of the pivoted pawl 21, is moved in an extended upward direction it will engage with the overhang- 95 ing ledge 24^b, and raise and hold the locking dog 24, out of engagement, as shown in Fig. 7, of the drawings.

As a means of permitting a limited movement between the draft bar or yoke 18, and the draft block or head 17, the upper and lower plates of the draft block are connected by means of vertical bolts 17^a, surrounded by spaced sleeves or spools 17^b, the latter being permitted to slide or travel in the slot 100 or guideway 18^c, formed by the spaced sides of the draft yoke 18, and it is obvious that this slotted arrangement between the bar or yoke 18, and the rear sleeve or spool 17^b, of the draft block will permit the draft bar 110 18, when the implement is in the position shown in Fig. 1, or when detached, or when the tractor is slackened, to be moved rearwardly from the position shown in Fig. 1, to that indicated in Figs. 3 and 4, without 115 moving the draft block 17, and its connections, so that when the disk harrow is attached or moved forwardly the disk gangs will assume a predetermined angular position, in accordance with the position given 120 to the draft bar or yoke 18.

The draft connections or bars, leading from the draft appliance to the front and the rear disk gangs, comprise longitudinally movable draft bars 25, leading from 125 the draft block or head 17, and connected to the inner ends of the front disk gangs, through the medium of pivot bolts 25^a, secured to the inner axle boxes 6^a, said draft bars 25, being provided with upwardly and 130

rearwardly extending draft links 25^b, connected to the inner ends of the bars 9 of the front gang frames by means of pivot bolts 25^c, and the draft connections, leading to 5 the rear gangs and the ends of the rear frame unit, comprise rearwardly diverging draft or reach bars 26, the latter, in the present instance, being pivotally connected to the pivoted portions of the rear gangs by 10 means of bearing plates 26^a, said bearing plates 26^a, being suitably secured to the gang frames 11, and surrounding the pivot bearing bolts 17, and by reason of this construction it will thus be seen that the draft 15 or reach bars 26, are indirectly connected to the outer ends of the rear harrow frame or bar 13, and it will also be observed that the rear ends of the draft or reach bars 26, are provided with downwardly and rearwardly 20 extending brace members 26^b, suitably secured to the central axle boxes of the rear disk gangs.

As a means of flexibly connecting the forward ends of the draft or reach bars 26, to 25 the ends of the draft links 25^b, as well as equalizing the draft movements or stresses given to the draft bars 26, and also guiding the latter and the draft links 25^b, in their forward and rearward movements in adjusting 30 the disk gangs, the forward ends of the draft or reach bars 26, are pivotally connected to a transversely extending equalizing bar 27, flexibly connected to the rear ends of the draft links 25^b, by means of 35 flexibly connected links 28, and as a means of longitudinally and vertically guiding the equalizing bar 27, and its connections, the equalizing bar 27, in the present instance, is provided with guide sleeves 27^a, 40 and a cross guide plate 27^b, connected by means of connecting bolts 27^c, said parts 27^a and 27^b, forming a guide opening to receive and contain a guide member 16^c, formed at the rear end of the fixed draft 45 element or median reach bar 16.

It will be seen that the connections of the draft links 25^b, with the links 28, and the connections of the latter, with the equalizing bar 27, and the pivoted connections of 50 such equalizing bar 27, with the forwardly converging reach bars 26, are arranged at points equally distant from the longitudinal center of the harrow or the line of draft thereof.

When the disk gangs are in their non-angled or parallel transporting position, as 55 shown in Fig. 1, of the drawing, and it is desired to positively prevent any rearward travel or retrograde movements of the draft 60 bar or yoke 18, while being transported, the rear end of such draft bar may be blocked or locked by throwing the pivoted bail member 29, from its full line released position, shown in Figs. 1 and 3, of the drawings, to its dotted line position, shown in

Fig. 1, of the drawings, thereby positively locking the parts so that the disk gangs will be positively held in their parallel transporting position, and when the harrow is attached to a tractor and it is desired to 75 move the disk gangs to an angular working position, the bail member 29, may be thrown rearwardly, and the draft bar or yoke 18, being attached to a tractor, or in other words being anchored relative to the 80 front draft frame, as the hand lever 19 is worked rearwardly, the stub-pole 8, and the draft frame member, and its connections, and relatively longitudinally fixed draft bars 5 and 8, and fixed draft bars 15, connected to the reach bars 16, will be moved forwardly relatively, thereby carrying the pivoted portions of the front disk gangs and the inner portions of the rear disk gangs 85 forwardly relative to the fixed draft members and imparting an angular position to the same in an obvious manner, in view of the construction above described and as illustrated in the accompanying drawings.

As a means of vertically supporting the 90 inner ends of the rear tillage gangs in a common horizontal plane in their various adjusted positions, the rear frame unit 13, is provided with brackets 30, said brackets 30, being provided with guide slots 30^a, 95 adapted to slidably receive and contain horizontally extending guide straps 31, suitably secured to the inner ends of the rear gang frames.

From the foregoing description, taken in 100 connection with the accompanying drawings, the operation and advantages of my invention will be readily understood.

Having thus described one of the embodiments of my invention, what I claim 105 and desire to secure by Letters Patent is:—

1. In a tillage implement, the combination with front and rear frame units each provided with longitudinally fixed and movable draft connections; of a hand lever 110 interposed between said fixed and movable draft members of said front unit and provided with lever actuated adjusting and locking mechanism for engaging said movable draft connections.

2. In a tillage implement, the combination with a front frame unit provided with longitudinally fixed and movable draft connections; of a hand lever interposed between said longitudinally fixed and movable draft members and provided with hand lever actuated pawl and rack adjusting and locking mechanism for engaging and moving said movable draft connections, said mechanism including a movable draft yoke and 120 a slideable block connected to said movable draft connections.

3. In a tillage implement, a plurality of frame units and tillage gangs, longitudinally fixed and movable draft members 130

- flexibly connected to said frame units and gangs, and a fixed draft element connected to one frame unit and to the fixed draft members of the other at points equally distant from the line of draft.
4. In a tillage implement, a plurality of frame units and tillage gangs, longitudinally fixed and movable draft members flexibly connected to said frame units and gangs, and a fixed reach bar connected to some of said fixed draft members and guiding said movable draft members at points equally distant from the line of draft.
5. In a tractor drawn tandem tillage implement, front and rear frame units including pivoted tillage gangs and anti-tilting devices, relatively fixed and movable draft members flexibly connected to said frame units and said gangs for angularly adjusting said gangs relative to each other, and a fixed median draft element on one of said units connected to and guiding said fixed and movable draft members, respectively.
6. In a tillage implement, flexibly connected tandem frame units, draft connections including a fixed guide member between said frame units movable relatively to each other and operable in one direction by the forward draft of the tractor for relatively adjusting said frame units, and lever actuated mechanism between said draft connections for manually adjusting said draft connections in an opposite direction.
7. In a tractor drawn tandem tillage implement, front and rear frame units including pivoted tillage gangs, relatively fixed and movable draft members flexibly connected to said frame units and the inner and intermediate portions of said gangs for angularly adjusting said frame units and gangs relative to each other, and a fixed draft element connected to and guiding said fixed and movable draft members, respectively.
8. In a tillage implement, front and rear frame units and pivoted tillage gangs, relatively fixed and movable draft members flexibly connected to said frame units and gangs for moving said frame units and angularly adjusting said gangs relative to each other, and a median reach bar connected to some of said fixed draft members and provided with a guide slidably engaged by said movable draft members.
9. In a tillage implement, a plurality of tandem frame units and tillage gangs, longitudinally fixed and movable draft members flexibly connected to said frame units and to the inner and intermediate portions of said tillage gangs, and a fixed median draft member connected to one of said frame units and the fixed draft members of the other and slidably engaging and guiding the intermediate portions of said movable draft members.
10. In a tillage implement, the combination with a plurality of tillage gangs and relatively fixed and movable draft connections flexibly connected therewith; of a hand lever and lever actuated adjusting and locking mechanism interposed between said fixed and movable draft connections, and means for releasing said lever actuated adjusting and locking mechanism by said hand lever.
11. In a tractor drawn tandem tillage implement, front and rear frame units including horizontally movable pivoted tillage gangs, relatively movable draft means connected to said frame units and gangs and movable in one direction by the implement drawing tractive force for angularly adjusting said gangs, and manually operable lever actuated mechanism for moving said draft means in an opposite direction and locking it against return movement.
12. In a tillage implement, a plurality of tillage gangs and longitudinally fixed and movable draft connections flexibly connected to the inner and intermediate portions thereof, a hand lever, lever actuated adjusting and locking mechanism interposed between said fixed and movable draft connections, and means for releasing said locking mechanism by said adjusting mechanism after the release of the latter by said hand lever.
13. In a tractor drawn tandem tillage implement, a plurality of frame units and tillage gangs, relatively longitudinally fixed and movable draft connections flexibly connected to said frame units and the inner and intermediate portions of said gangs, a fixed draft guide member carried by one of said frame units connected to some of said fixed draft connections and guiding said movable draft connections between said frame units.
14. In a tillage implement, a plurality of tillage gangs and relatively longitudinally fixed and movable draft connections flexibly connected to the inner and intermediate portions of said gangs, a longitudinally fixed guide member for said movable draft connections, means for actuating said movable draft connections by the forward draft on the implement for angularly adjusting said gangs in one direction, and lever actuated adjusting and locking mechanism for actuating said movable connections and gangs in an opposite direction.
15. In a tractor drawn tillage implement, tandem frame units and angularly adjustable tillage gangs carried thereby, relatively adjustable draft means flexibly connected to said frame units and gangs and movable in one direction by the forward draft of the tractor for adjusting the relative positions of said frame units and gangs, and manually operable lever and lever actuated

locking mechanism between said relatively adjustable draft means for actuating the latter in an opposite direction.

16. In a tillage implement, front and rear frame units and pivoted tillage gangs, relatively fixed and movable draft members flexibly connected to said frame units and gangs for adjusting said gangs relative to each other, an equalizing bar flexibly connected to said movable draft members between said front and rear frame units, and a median draft member connected to some of said fixed draft members and slidably engaged by said equalizing bar and guiding said movable draft members between said frame units.

17. In a tractor drawn tandem tillage implement, a plurality of frame units and tillage gangs, relatively longitudinally fixed and movable draft connections flexibly connected to said frame units and the inner and intermediate portions of said gangs at points equally distant from the line of draft, a fixed central draft guide member on one of said frame units connected to the fixed draft connections leading to the other and guiding said longitudinally movable draft connections between said frame units.

18. In a tractor drawn tandem tillage implement, front and rear frame units including horizontally movable pivoted tillage gangs, relatively movable draft bars and links flexibly connected to said frame units and gangs and operable in one direction by the implement drawing tractive force for angularly adjusting said gangs, manually operable lever mechanism for connecting and adjusting said movable draft means and for moving the latter in an opposite direction, and locking mechanism for automatically preventing retrograde movement of said movable draft means as moved by said lever mechanism.

19. In a tillage implement, a plurality of tandem frame units and tillage gangs, longitudinally fixed and movable draft members flexibly connected to said frame units and to the inner and intermediate portions of said tillage gangs, an equalizing bar flexibly connected to said movable draft members, lever actuated means for connecting adjusting and locking said fixed and movable draft members relative to each other, and a fixed median draft member connected to one of said frame units and the fixed draft members of the other and provided with a guide member slidably engaged by said equalizing bar and guiding the intermediate portions of said movable draft members.

20. In a tillage implement, flexibly connected tandem frame units, draft connec-

tions including a draft bar having a toothed rack between said frame units movable relatively to each other and operable in one direction by the forward draft of the tractor for relatively adjusting said frame units, a hand lever between said draft connections and provided with a pawl adapted to engage said toothed rack for manually adjusting said draft connections in an opposite direction, and a locking dog engaging said toothed rack to prevent retrograde movement of the latter when moved by said hand lever and pawl, said locking dog being engaged by said pawl when the latter is moved above its rack releasing position to fully release said rack for movement in an opposite direction.

21. In a tractor drawn tandem tillage implement, front and rear frame units including pivoted tillage gangs, relatively fixed and movable draft members flexibly connected to said frame units and the inner and intermediate portions of said gangs and operable by the implement drawing tractive force of the tractor for adjusting said frame units and gangs relative to each other, a reach bar connected to some of said fixed draft members and slidably engaging said movable draft members at points equally distant from the common longitudinal centers of said frame units and tillage gangs, and means for actuating, adjusting and locking said fixed and movable draft members and frame units relative to each other.

22. In a tractor drawn tandem tillage implement, front and rear frame units including pivoted tillage gangs, relatively fixed and movable draft bars and reach members flexibly connected to said frame units and to the inner and intermediate portions of said gangs including a longitudinally movable draft appliance operable by the implement drawing tractive force of the tractor for adjusting said frame units and gangs relative to each other, a fixed draft member connected to some of said fixed draft members and guiding said movable draft members intermediate said frame units and tillage gangs, and lever actuated means on said front frame unit for actuating, adjusting and locking said fixed and movable draft members and frame units relative to each other.

In testimony whereof I have affixed my signature in the presence of two witnesses.

FREDERICK C. WARNE.
